SHOE REPAIR MACHINE

Earl L. Vanderpool, Poplar Bluff, Mo., assignor of
one-fourth to Samuel H. Alexander, Poplar
Bluff, Mo., and one-fourth to David X. Green-
berg, Kirkwood, Mo.

Application October 1, 1938, Serial No. 232,857

1 Claim. (Cl. 51—166)

This invention relates to shoe repair machines, and has for the primary object, the provision of a device of this character which will render shoe repairing less tiring on the operator, in that the 5 operator may remain in one position and readily bring the various motor driven tools into position for carrying out the various operations in repairing shoes.

Another object of this invention is the provision 10 of a single suction means which will efficiently collect cuttings from all tools of the cutting and abrading types and deliver the cuttings to a single collecting device for emptying after the expiration of a given length of time.

15 With these and other objects in view, the invention consists of certain novel features of construction, combination and arrangement of parts to be hereinafter more fully described and claimed.

For a complete understanding of my invention, 20 reference is to be had to the following description and accompanying drawings, in which:

Figure 1 is a side elevation illustrating the shoe repairing and finishing machine constructed in accordance with my invention.

25 Figure 2 is a top plan view illustrating the same.

Figure 3 is a sectional view taken on the line 3—3 of Figure 2.

Figure 4 is a sectional view taken on the line 30 4—4 of Figure 3.

Figure 5 is a detail sectional view showing the means of adjustably securing the split clamp.

Referring in detail to the drawings, the numeral 5 indicates a pedestal, including a vertically arranged post 6 on which is journalled a tool mounting 7 preferably in the form of a drum or of cylindrical shape. However, the tool mounting 7 may be of any other configuration and provides therein a chamber 8 open to the upper end of the post 6 which is hollow as shown at 9. A partition 10 is arranged in the post a limited distance above its upper end for closing the portion 9 of the post to the lower portion thereof. The hollow portion 9 of the post has an opening 11 to

45 which is connected a suction fan 12 of a conventional construction driven by an electric motor 13. The suction fan 12 is equipped with an exhaust pipe 14 which may lead to a collecting receptacle, not shown, or if desired, a conventional type of dust collecting bag may be connected to the fan 12 in lieu of the pipe 14. Thus it will be seen that when the fan 12 is in operation suction will be had in the chamber 8 of the tool mounting by way of the opening 11 in the hollow

50 portion 9 of the post.

Mounted on the periphery of the tool mounting 7 are motor supporting brackets 17 carrying electric motors 16 and 16', the ends of the shafts thereof having secured thereon the different types of tools employed in shoe repairing and the tools 5 which are of the cutting type or of the abrasive type have associated therewith guards 17' to which suction pipes 18 are connected or form integral parts thereof. The suction pipes connect with the chamber 8 of the tool mounting and have 10 located therein valves 19 of the damping type. The suction pipes which lead to the cutting tools of one of the motors 16 are connected to a single operating rod 19' which is provided with 15 a handle 20 and a projection 21. The projection 21 connects or engages with an electric switch 22' for controlling the operation of the motor. The purpose is to close the switch when the valves are opened so as to set the motor in 20 operation and when the valves are opened suction from the chamber 8 will draw therein the cuttings from the tools when the shoe is being repaired.

As shown further in Figure 2, one of the motors 16 has associated therewith only a single suction pipe and the valve thereof has connected thereto an operating rod 22 which also is adapted to control the switch 23' of that motor. Without departing from the present invention, it is 25 to be understood that the valve operating means may be varied, that is, the operating means may be arranged to operate one or more valves or a single valve. In either instance, it is to be understood that when the valves are moved into open position the switches are operated to close the circuits to the motors and when the valves are moved into closed position the switches are operated to break the circuit to the motors. Further, it is to be understood that when one of the motors 30 16 is in operation, the other motor 16 is left inoperative and the valves of this motor remain closed so that all of the suction acts to take the cuttings away from the tool of the motor 35 which is in operation.

Electric collecting rings 24 are mounted on and 40 insulated from the tool mounting and surround the post as clearly shown in Figure 3, and are engaged by brushes 25 carried by a support 26 on the post and insulated therefrom. It is to be 45 understood that the brushes 25 are connected in an electric circuit of any conventional type and also the electric motor 13 of the suction fan so that the electric motor 13 will be in operation whenever one of the motors 16 is in operation. 50 55

Carried by the tool mounting and surrounding the post is a split sleeve 27 equipped with a suitable adjusting medium 28 which will permit the sleeve to be brought into gripping relation with the post for holding the tool mounting against accidental rotation. However, the tool mounting may be freed for the purpose of rotation to bring the desired motor and its tools into a position adjacent the operator.

It is believed that the foregoing description, when taken in connection with the drawings will fully set forth the construction and advantages of this invention to those skilled in the art to which such a device relates, so that further detailed description will not be required.

Having thus described my invention, what I claim is:

A shoe repairing machine comprising a pedestal, a drum journalled on said pedestal having a chamber, electric motors mounted on said drum and having connected thereto shoe repairing tools, switches for said motors, suction pipes connected with the chamber of the drum and associated with the shoe repairing tools to receive cuttings, valves in said suction pipes, operating means for said valves and switches whereby on the opening of said valves said motors will be set in operation, and a suction means connected to the chamber of the drum.

EARL L. VANDERPOOL. 15
